UNITED STATES PATENT OFFICE.

CLYDE L. KNOTT, OF BEVERLY, MASSACHUSETTS, ASSIGNOR TO UNITED SHOE MACHINERY CORPORATION, OF PATERSON, NEW JERSEY, A CORPORATION OF NEW JERSEY.

PRESS.

1,416,721.

Specification of Letters Patent. Patented May 23, 1922.

Application filed May 21, 1920. Serial No. 383,267.

To all whom it may concern:

Be it known that I, CLYDE L. KNOTT, a citizen of the United States, residing at Beverly, in the county of Essex and State 5 of Massachusetts, have invented certain Improvements in Presses, of which the following description, in connection with the accompanying drawings, is a specification, like reference characters on the drawings 10 indicating like parts in the several figures.

This invention relates to presses and more particularly to presses of the type employed in cutting sheet material by the use of freely movable dies.

15 A very efficient type of press, disclosed in United States Letters Patent No. 921,503, granted May 11, 1909, on an application filed by Arthur Bates and known commercially as the clicking machine, comprises 20 characteristically a work supporting bed of considerable area and a presser member having a pressure surface of less area than that of the work supporting bed and movable laterally over the bed into and out of 25 selected operative positions with respect to dies wherever they may be located upon the work on the supporting bed. Commonly the presser member is moved laterally of the bed under direct manual control and power 30 means is provided for reciprocating the presser member during pressure applying operations, the latter comprising a post upon which the presser member is mounted for oscillation about the axis of the post.

35 As originally designed the clicking machine was intended primarily for cutting blanks from relatively thin sheet material such as upper leather utilized in the manufacture of boots and shoes and for work of 40 this character the machine has given complete satisfaction. However, in operating upon material which is much thicker and denser than the material used for the uppers of shoes, or upon fabrics arranged in layers, 45 it is found that the presser member tips away from the bed during the application of pressure, due to yielding of the frame of the machine, and that there is sometimes failure to drive the die completely through 50 the work.

It is an object of this invention to provide an improved press which, while re-

taining all of the advantages of the commercial clicking press, will be entirely satisfactory in an extended field of usefulness, 55 more particularly in the cutting of relatively heavy and dense material and of fabrics in a multiplicity of superposed layers.

To this end the invention comprises in 60 one aspect a press wherein the movable presser member has a direct bearing contact with a portion of the frame of the machine that is especially effective to receive and absorb the stresses and strains incidental to 65 pressure applying operations.

In another aspect the invention resides in a press wherein the lower of the two bearings for the post which supports the presser member is provided with an exterior 70 bearing surface for engagement with a correspondingly shaped bearing surface on an extension rigid with the presser member, the arrangement being such that the presser member is backed by the bearing surface to 75 prevent tipping of the presser member during pressure applying operations over any and all parts of the work supporting bed.

In still another aspect the invention comprises a press wherein the movable presser 80 member has a bearing for co-operation with another bearing on the machine located considerably above the plane of the work supporting bed and above the point of support of the presser member.

85 Another feature of importance in the construction by which the presser surface of the presser member is held in a plane parallel with the surface of the work support is that which relates to the strengthening 90 of the frame of the machine and particularly of the C-shaped portion which furnishes the support for the post upon which the presser member is mounted. In prior constructions the tendency to bend or twist 95 the C-shaped portion of the frame during the application of pressure was especially noticeable when the presser member occupied one of its operative positions at the extreme opposite ends of the bed. In the 100 illustrative construction, this disadvantage is overcome by providing flanges or strengthening ribs on the C-shaped portion of the frame which are located respectively

in line with the longitudinal axis of the presser member when the latter is positioned first in one and then in the other extreme operative position at the opposite ends of 5 the work supporting bed.

Other features of the invention and other combinations of parts will be described in detail in the specification and pointed out in the appended claims.

10 In the drawings:—

Figure 1 is a view in side elevation of an illustrative embodiment of the invention;

Fig. 2 is a plan view of the machine shown in Fig. 1; and

15 Fig. 3 is a sectional view of a lower bearing for the post.

In the illustrative construction the frame 4 provides a support for a work supporting bed 6 and also bearings 8 and 10 for a post 20 12 upon which is mounted the presser member 14. As shown the presser member is fixedly secured to the post 12, the latter being mounted rotatably in its bearings 8 and 10. In an equivalent construction the 25 presser member may be rotatably mounted on the post in which case the latter is fixed against rotation. For operating the presser member means is provided for reciprocating the post 12, the said means comprising, in 30 the illustrative construction, a horizontal shaft 16 located in bearings in the frame of the machine and arranged to be driven from the power pulley 18 loosely mounted on the shaft and arranged to be connected to the 35 shaft through a clutch mechanism (not shown) upon actuation of the starting means which comprises a handle 20. Extending between the shaft 16 and the post 12 is a link 22 pivotally attached to the upper end 40 of an eccentric strap 24 surrounding an eccentric (not shown) on the end of the shaft 16. For a more complete disclosure of the operating means for the presser member, reference should be had to said Patent No. 45 921,503.

An important feature of the invention resides in the provision of means for taking up the stresses on the presser member during pressure applying operations and especially in such a construction as will relieve the post from all or a greater part of the strains and stresses heretofore imposed upon it in machines of this type. In the 50 illustrative machine the presser member 14 has extending rearwardly from the presser member and in alinement with the longitudinal axis of the presser member an arm or extension 30 rigid with the presser member and having a portion 32 provided with 55 a bearing surface for engaging an exterior bearing surface 33 on the lower bearing 10 for the post. It will be clear that there is a considerable exterior bearing surface 33 on said bearing 10 since the portion 32 60 moves up and down over said surface and

also rotates around the surface during oscillation of the presser member 14 over the work supporting bed. It will be understood that the arm 30 with its portion 32 in engagement with the bearing 10 will back up 70 the presser member 14 during pressure applying operations and will prevent most effectively any tendency of the presser member to tip away from the bed during such operations.

75 While the bearing 10 in the embodiment of the invention illustrated in Fig. 1 comprises a member or sleeve separate from the frame, it affords a firm bearing surface since it is set down into the frame and is backed up 80 on the side toward the block or bed 6 by a flange or web 13 cast with the frame and designed to extend about 90° around the surface of the sleeve bearing 10. Moreover, the post 12 furnishes additional strengthening or backing means for the bearing sleeve 10 and hence the construction is such as to provide an unyielding and effective bearing surface 33 for co-operation with the portion 32 of the presser member. Another 85 arrangement of co-operating bearing members for taking the thrust of the presser member 14 during pressure applying operations is shown in Fig. 3 of the drawings 90 wherein the lower bearing 11 is disclosed 95 as an integral part of the machine frame, the exterior surface of the bearing being planed to furnish the bearing surface 33 for co-operation with the bearing surface on the member 32. By these constructions 100 the post is relieved of all the strains and stresses to which it was subjected in prior machines and a bearing is made on the frame itself for the presser member whereby the 105 general construction is greatly strengthened.

Extending upwardly from the presser member 14, in the illustrated construction, is an arm 34 having a bearing 36 which engages the upper end of the post 12 above the upper bearing 8. It will be observed, 110 therefore, that the post and the presser member each have a plurality of bearings which are widely spaced from each other, the bearings for the presser member being so positioned as to furnish most effective resistance 115 to the tendency of the presser arm to tip away from the work supporting bed.

For strengthening the frame of the machine and more particularly the upper part of the C-shaped portion which supports the 120 post and consequently receives the stresses during pressure applying operations, there is provided a novel form of C-shaped frame wherein, as shown, flanges are integrally formed with the C-shaped portion of the 125 frame, the upper portions of the flanges extending respectively in line with the longitudinal axis of the presser member when the latter is first in one and then in the other of its extreme positions at opposite 130

ends of the work supporting bed. Thus, viewing Figure 2 from the front of the work supporting bed, the flange 38 at the right of the operator serves to back up the presser member completely when the latter is in extreme position at the left end of the cutting bed while the flange 40 is effective in a similar way when the presser member is at the extreme right over the opposite end 5 of the bed 6. In intermediate positions of the presser member 14 both flanges 38, 40 co-operate to take the strains incidental to operations on the work.

From the foregoing description it will be 15 understood that sheet material to be cut is placed upon the work supporting bed 6 and a die or other cutter positioned in the desired location on the material, these operations taking place while the presser member 20 is at one side of the bed. When the work is ready, the operator moves the presser member 14 over the cutter or die and causes power operation of the machine through the starting handle 20. Subsequently the presser 25 member 14 is displaced to one side of the die which may then be freely manipulated in positioning it afresh upon the work, and the work itself inspected and, if necessary, repositioned prior to another cutting operation.

Having thus described the invention, what is claimed as new and desired to be secured by Letters Patent of the United States is:—

35 1. In a machine of the class described, a work supporting bed, a presser member movable laterally over the bed and also toward and from the bed in pressure applying operations, a post for supporting the presser member, said presser member having a portion arranged to provide a supporting connection between the presser member and the post, a plurality of bearings for the post and a plurality of supporting bearings for 40 the presser member so arranged as to relieve most of the strain on the post during pressure applying operations.

2. In a machine of the class described, a work supporting bed, a presser member movable laterally over the bed and also toward and from the bed in pressure applying operations, means comprising a post for operating the presser member, a plurality of bearings for the post in the frame of the machine, a bearing for the presser member on the post, and a bearing on the frame of the machine for said presser member whereby the strain of pressure applying operations is borne in large part directly from the 55 presser member to the frame of the machine.

3. In a machine of the class described, a work supporting bed, a presser member movable laterally over the bed and also toward and from the bed in pressure applying 60 operations, means comprising a post for

operating the presser member, and upper and lower bearings for the post in the frame of the machine, said presser member having a portion arranged to engage movably upon a bearing surface on the frame of the machine, whereby the presser member is supported directly by the frame of the machine during a pressure applying operation in any selected position of the presser member.

4. In a machine of the class described, a work supporting bed, a presser member movable laterally over the bed and also toward and from the bed in pressure applying operations, said presser member having a bearing extension, means comprising a post for 80 operating the presser member, a plurality of bearings in the frame of the machine for supporting the post for rotation therein, means for connecting the presser member to the post, a bearing on the post for the presser member, and a bearing in the frame of the machine arranged to be movably engaged by said extension from the presser member, whereby the presser member is supported directly by the frame of the machine during 85 a pressure applying operation in any selected position of the presser member.

5. In a machine of the class described, a work supporting bed, a presser member movable toward and from the bed in pressure 90 applying operations, power means comprising a post upon which the presser member is mounted for operating the presser member, the machine frame having a portion provided with a bearing surface, and a 95 member rigid with the presser member and having a bearing surface to co-operate with the bearing surface on the frame to prevent tipping of the presser member during pressure applying operations.

6. In a machine of the class described, a work supporting bed, a presser member movable toward and from the bed in pressure applying operations, power means comprising a post upon which the presser member 100 is mounted for operating the presser member, upper and lower bearings in the frame for said post, the lower bearing having also an exterior bearing surface, and an arm rigid with the presser member and having 105 a surface for engagement with the exterior bearing surface on the lower bearing.

7. In a machine of the class described, a work supporting bed, a presser member movable toward and from the bed in pressure 110 applying operations, power means comprising a post upon which the presser member is mounted for operating the presser member, upper and lower bearings for the post in the frame of the machine, said lower bearing having an exterior bearing surface, an arm rigid with the presser member and having 115 a bearing surface arranged to engage slidably with the exterior bearing surface of said lower bearing, and an arm extending 120

125 130

from the presser member and having a bearing on the post adjacent said upper bearing for the post.

8. In a machine of the class described, a work supporting bed, a presser member movable laterally over the bed and also toward and from the bed in pressure applying operations, power means comprising a post for reciprocating the presser member to effect pressure applying operations, a plurality of bearings for the post in the frame of the machine within which the post is mounted for both rotation and reciprocation, said lower bearing having also an exterior bearing surface, the presser member having a portion mounted to engage with said exterior bearing surface during both rotation and reciprocation of the presser member.

9. In a machine of the class described, a work supporting bed, a presser member movable toward and from the bed in pressure applying operations, power means, comprising a post upon which the presser member is mounted, for operating the presser member, a portion of the machine frame having a bearing surface, and an arm or extension rigid with the presser member and having a surface for engagement with said bearing surface on the machine frame, whereby the presser member is supported against lateral movement directly by the frame of the machine during a pressure applying operation.

10. In a machine of the class described, a work supporting bed, a presser member movable laterally over the bed and also toward and from the bed in pressure applying operations, means comprising a post for operating the presser member, a bearing in the frame of the machine for supporting the post for reciprocation therein, said presser member having an arm or extension provided with a bearing surface, and a bearing in the frame of the machine arranged to be engaged by the bearing surface on the extension from the presser member during pressure applying operations with the presser member in various selected positions with respect to the work supporting bed.

11. In a machine of the class described, a work supporting bed, a presser member movable laterally over the bed and also toward and from the bed in pressure applying operations, a post for supporting the presser member, and a bearing for the post in the frame of the machine, the machine frame and the presser member having co-operating bearing surfaces arranged to relieve the strain on the post during pressure applying operations.

12. In a machine of the class described, a work supporting bed, a presser member movable laterally over the bed and also toward and from the bed in pressure applying operations, a post for supporting the presser

member, a bearing for the post above the point of support of the presser member thereon, and co-operating bearing surfaces on the machine and on the presser member above the level of the work supporting bed 70 and the point of support of the presser member on the post.

13. In a machine of the class described, a work supporting bed, a presser member movable laterally over the bed and also toward 75 and from the bed in pressure applying operations, a post for supporting the presser member, bearings for the post in the frame of the machine above and below the point of support of the presser member on the 80 post, and co-operating bearings on the machine and on the presser member located above the upper bearing for the post.

14. In a machine of the class described, a work supporting bed, a presser member movable laterally over the bed and also toward 85 and from the bed in pressure applying operations, a post for supporting the presser member, upper and lower bearings in the frame of the machine for the post, said 90 presser member having a portion which surrounds the post to provide a supporting connection between the presser member and the post, and an arm extending from the presser member and having a bearing to engage the post above said upper bearing. 95

15. In a machine of the class described, a work supporting bed, a presser member movable laterally over the bed and also toward and from the bed in pressure applying operations, a member mounted in the frame of the machine and serving as a support for the presser member and containing the axis about which the presser member turns in moving laterally over the bed from one extreme operative position to the other at opposite ends of the bed, and flanges on the frame of the machine to strengthen the same and arranged respectively in line with the longitudinal axis of the presser member 100 when the latter is located first in one and then in the other of its extreme operative positions. 105

16. In a machine of the class described, a work supporting bed, a presser member 115 movable laterally over the bed and also toward and from the bed in pressure applying operations, and a post mounted in the frame of the machine and serving as a support for the presser member and containing 120 the axis about which the presser member turns in moving laterally over the bed from one extreme position to the other at opposite ends of the bed, said frame of the machine having a C-shaped portion to provide 125 bearings for the post and having spaced flanges to strengthen the C-shaped portion of the frame, the said flanges being so arranged as to extend from the frame each in line with the longitudinal axis of the presser 130

member when the latter is in one and then in the other of its extreme operative positions.

17. In a machine of the class described, a work supporting bed, a presser member movable laterally over the bed and also toward and from the bed in pressure applying operations, a post for supporting the presser member, the presser member being rigidly connected to the post, upper and lower bearings for the post located in the frame of the machine above and below the point of the support for the presser member, and an arm extending from the presser member and arranged to engage the post above the upper bearing for the latter.

18. In a machine of the class described, a work supporting bed, a presser member movable laterally over the bed and also toward and from the bed in pressure applying operations, a post for supporting the presser member, the presser member being rigidly connected to the post, upper and lower bearings for the post located in the frame of the machine above and below the rigid connection of the post and presser member, and bearing extensions of the presser member located above and below the rigid connection with the post and operative to support the presser member during a pressure applying operation.

19. In a machine of the class described, a work supporting bed, a presser member movable laterally over the bed and also toward and from the bed in pressure applying operations, a post for supporting the presser member constructed to rotate with

the latter, upper and lower bearings for the post in the frame of the machine, and an arm extending rearwardly with respect to 40 the presser member and the work supporting bed and having a bearing located above the upper bearing for the post and operative to absorb the lateral component of the thrust during the pressure applying operation. 45

20. In a machine of the class described, a work supporting bed, a presser member movable laterally over the bed and also toward and from the bed in pressure applying operations, a post for supporting the 50 presser member, a rigid connection between the post and presser member, upper and lower bearings for the post in the frame of the machine, and an arm extending from the presser member and having a bearing 55 surface arranged to engage a bearing surface on the frame of the machine in proximity to the lower bearing for the post.

21. In a machine of the class described, a work supporting bed, a presser member 60 movable laterally over the bed and also toward and from the bed in pressure applying operations, a post for supporting the presser member, a rigid connection between the post and presser member, upper and 65 lower bearings for the post in the frame of the machine, and a plurality of bearings for the presser member so arranged as to relieve the strain on the post during pressure applying operations. 70

In testimony whereof I have signed my name to this specification.

CLYDE L. KNOTT.
